DEPRESSIBLE SURFACE FOR FOLDING TABLES

Edmund N. Neckel, North College Hill, Ohio, assignor, by mesne assignments, to McGraw-Edison Company, a corporation of Delaware

Filed June 30, 1958, Ser. No. 745,613

7 Claims. (Cl. 223—37)

The invention relates to folding means for laundered articles, and particularly for articles of non-uniform thickness, or having, in the folded or unfolded condition, portions of irregular thickness. The invention will be described with particular reference to the folding of a garment provided with a collar, and wherein the collar need not be of the "dress-shirt" type.

The various kinds of folding tables—manual, semi-automatic or full automatic—have ordinarily employed collar blocks, or holders, of the stand-up type. These comprise arcuate bands or segments adapted, by suitable mechanism, to be expanded within the neckband and position the collar substantially in perpendicular or stand-up relation to the shirt body. More recently there has been a trend toward semi-laydown blocks and even full laydown. Both of these use expandable blocks of suitable shape within the neckband, giving the desired conformation but without complete flattening. These various block devices are usually positioned in a well below the table top.

The above types of collar holders are the ones best suited for dress shirts, as providing a well-formed collar from the standpoint of appearance and comfort—a good proportion of dress shirts being starched. There is another class of shirts, however, which is not governed by these considerations and may be folded with the collar in flattened condition. This class includes work shirts, various special shirts handled by the linen supply organizations, army shirts, etc. They constitute a considerable proportion, in some cases practically all, of the shirt work in certain laundries. For these situations it is desirable to have a holder designed for such work, eliminating the more expensive collar block.

In the folding of sport shirts the flattened collar has been the usual practice. These make up a fairly large proportion of the shirt work in commercial laundries handling general family work. Folding tables are available having a plain flat surface rather than a collar well and block. Also, some tables are fitted with a hinged plate which can be swung down to cover the collar block well.

These designs are suitable for their purpose, but do not satisfy the requirements for the industrial type shirts. The latter usually are made of thicker material and are bulkier than dress shirts. This is especially so as regards the collar portion. With shirt folders of conventional design, the forming or folding plate is hinged to be swung down substantially parallel and closely adjacent to the folding surface, on top of the shirt. The thickness of many work shirt collars would prevent the complete folding down of the folding plate if the collar rested on a flush, solid surface, coplanar with the rest of the table top. The folding plate could, of course, be hinged somewhat higher, or a shallow depression could be provided in the table top to receive the collar portion. These expedients might take care of some shirts fairly well, but others would not be held snugly nor the collar flattened.

An object of the present invention is to provide, in a

2

folding machine of the character described, a yieldable supporting area for a work piece having portions of non-uniform thickness.

A further object of the invention is to provide yieldable supporting means as defined in the last preceding paragraph which cooperates with other folding machine parts in preventing displacement of the article during folding and also flattens the article for better appearance and easier packing.

10 Other objects and advantages will be apparent from a study of the following specification describing, in conjunction with the accompanying drawings, one embodiment of the invention.

In the drawings:

15 Fig. 1 is a top plan view of a fragmentary portion of a shirt folding table.

Fig. 2 is a sectional view taken on the line 2—2 of Fig. 1.

20 Fig. 3 is a view taken similarly to Fig. 2 but showing the operating elements in a different operating position.

Figs. 1 and 2 show a flat topped, folding table 12, supported on fixed frame members 13, 14 which are shown only in fragmentary detail since their structure will be well understood by those in the art. The table 25 is cut away at 12a to receive the down turned collar 15a and adjacent portions of a shirt 15, said collar being yieldably supported on a yielding supporting plate 16. Plate 16 is swingable downwardly on a hinge 17 attached to the under side of table 12 in the neighborhood of a concavity 12b which serves as a tray for holding a supply of paper strips 18 having adhesive material on one end, the strips being of course used by the operator to bind the shirt in folded position at the completion of the folding operation. The hinge axis 17 is located at a convenient 30 position to give a suitable angle of movement to the supporting means when the latter moves down to the position shown in Fig. 3 as will appear.

The support plate is biased to upper position by a helical spring 19 threaded on a bolt 20, and against a stop 40 20a, the free end of the spring abutting a fixed frame member 21. The bolt 20 is pivotally attached, to the support plate 16 at a clevis bracket 22. Any means biasing the supporting plate upwardly in the present instance would be effective to accomplish the purpose.

45 Plate 23 is the usual folding plate around which portions of a shirt, including sleeves, tails, etc., are folded. In actual practice its hinge axis 23a is closer to the plane of the folding table 12, but the spacing between the table and plate 23 is here exaggerated to allow a showing of 50 the interposed fabric plies of the shirt.

When the plate 23 is swung from the position of Fig. 2 to that of Fig. 3 the plate will depress the collar and its yieldable support plate 16 to the Fig. 3 position. Plate 23 is shown as provided with a clamp 24, pivoted at 24a and with an over center biasing spring 25. When plate 23 is swung down to working position as aforesaid, and parts of the shirt are folded over the plate, the clamp arm 24 may be swung counterclockwise, dotted in Fig. 3, to hold these folded parts pending completion of final folding steps.

It will be obvious that the invention comprises a depressible support which cooperates with a superimposable member to accommodate at least a portion of a workpiece therebetween, the invention being useful when the workpiece has portions of non-uniform width.

What is claimed is:

1. Folding means of the character described for the folding of articles of non-uniform thickness, said folding means comprising a garment folding table having a fixed working surface, a portion of said surface being cut away, a supporting member movably maintained below and in registry with said working surface and adapted to

receive thereon a thicker part of said article, and means for resiliently and continuously biasing said supporting member upwardly towards the plane of said working surface.

2. Shirt folding means of the character described for the folding of shirts of non-uniform thickness by reason of the extra thickness in the neighborhood of the collar, said folding means comprising a table having a fixed upper lay-out surface, and a lower surface, a part of said table being cut away to provide an aperture, a supporting plate disposed below said aperture and in registry therewith, and adapted to receive the collar when the shirt is laid out on said upper surface, and means for resiliently biasing said supporting plate upwardly in the direction of the plane of said upper working surface.

3. Shirt folding means as defined in claim 2 wherein said supporting plate is hingedly connected at one end thereof to the lower face of said table, and wherein the other end of said supporting plate is provided with helical spring means biasing it upwardly in the direction of said working surface.

4. Folding means of the character described for the folding of articles of non-uniform thickness, said folding means comprising a garment folding table having an upper plane surface for the folding of a garment thereon, a portion of said table being resiliently depressible from its normal position at said plane surface and adapted to

5

support a thicker portion of said article, and said table having movably connected thereto a member adapted to overlie said depressible portion but being vertically spaced therefrom when in garment-folded position whereby said thicker portion is maintained between said depressible portion and said overlying member.

5. Folding means of the type defined in claim 4 and wherein means is provided for resiliently and continuously biasing said depressible portion upwardly.

10

6. Folding means of the type defined in claim 1 comprising, in combination therewith, means disposed above the cut away portion of said fixed working surface, and spaced vertically above said supporting member, whereby to be adapted to receive said thicker part therebetween.

15

7. Shirt folding means of the type defined in claim 2 comprising, in combination therewith, a member spaced vertically above said supporting plate whereby the collar of said shirt is held between said member and said supporting plate.
